UNITED STATES PATENT OFFICE.

ANDREAS TENGVALI, OF HELSINGBORG, SWEDEN.

LETTER-FILE.

SPECIFICATION forming part of Letters Patent No. 615,115, dated November 29, 1898.

Application filed February 5, 1897. Serial No. 622,164. (No model.)

To all whom it may concern:

Be it known that I, ANDREAS TENGVALL, merchant, a subject of the King of Sweden and Norway, residing at Helsingborg, Sweden, 5 have invented certain new and useful Improvements in Letter-Files; and I do hereby declare the following to be a full, clear, and exact description of the invention, such as will enable others skilled in the art to which it applies to make and use the same, reference being had to the accompanying drawings, and to letters of reference marked thereon, which form a part of this specification.

My invention relates to an arrangement for 15 holding together bills, letters, or other documents in files in such a manner that one or more of the filed papers can be readily removed from their board lids or covers.

Referring to the drawings, in which like 20 letters refer to like parts in the several views, Figure 1 is a plan view of my improved device, showing the covers or lids open. Fig. 2 is a longitudinal section showing the covers closed; and Fig. 3 is a view of a modification, 25 showing the device in elevation, the retaining device being secured to the lower lid.

a designates two lids or covers flexibly connected to a back *h* in such manner as to lie flat when open. To the back *h* is secured a 30 hinge-piece consisting of a sleeve *g*, having a securing-flange *g'*. The flange is riveted or otherwise secured near one edge of the back *h* in such manner that the sleeve *g* will lie against one lid or cover at the point of connection with the back.

The documents to be filed are secured between the covers by means of pins *c*, which are connected by a cross-bar *c'*, journaled in the sleeve *g*. This cross-bar *c'* is bent at 40 right angles to the plane of the pins, which offsets them some distance from the back *h*, holding the pins perpendicular to the covers and parallel with the back when the file is closed. The sleeve *g* may also be secured to one of the covers, if desired, the positions of the pins remaining the same relative to the back when the file is closed. Over the pins *c* are placed perforated binder-plates *d*, the perforations registering with the pins, and between

these plates the letters or documents to be filed are held, perforations having been previously made in the letters to register with the pins. A second set of pins *b*, similar to the first, but not having their cross-bar bent at an angle to the plane of the pins, pass 55 through a second set of perforations in the plates and papers. The pins *b* are shown as being wider apart than those of the other set; but they may be made much closer together or the same width, as shown by the dotted lines. In each case one of the pins in each set will be between those of the other, or one set may be slightly in advance of the other, so that the distance between the pins of each set and the corresponding perforations in the 60 plates will be variable to any extent consistent with the size of the documents to be filed.

To remove a letter or other document from the center of the file, the hand is passed under that one next above the one to be removed 70 and the upper plate and pins *b* and letters above the one to be removed are lifted out. The desired letter can then be removed, all those below it being held in position by the pins *c*, and the pins *b*, with the letters thereon, 75 can then be returned to their position, all the perforations in the lower letters having been held in register by the lower pins *c* and those in the upper letters having been similarly held by the pins *b*.

Having thus described my invention, what I claim as new, and desire to secure by Letters Patent, is—

1. A letter-file comprising a back and sides or covers hinged thereto, two filing-pins for 85 the reception of the letters, pivotally connected with the back to hold said letters parallel with the sides or covers when the file is open or closed, and two auxiliary retaining-pins adapted to pass through the file contents 90 from an opposite direction and at points other than those through which the filing-pins pass, for the purpose set forth.

2. A letter-file comprising a back and sides or covers hinged thereto, two filing-pins for the 95 reception of the letters, pivotally connected with the back to hold said letters parallel with the sides or covers when the file is open or

closed, two auxiliary retaining joined pins adapted to pass through the file contents from an opposite direction and at points other than those through which the filing-pins pass, and 5 binding-plates fitting loosely on the filing and retaining pins and forming an edge binding for the file contents, substantially as set forth.

In testimony whereof I affix my signature in presence of two witnesses.

ANDREAS TENGVALL.
